UNITED STATES PATENT OFFICE

WILLIAM B. VANDEGRIFT, OF MINNEAPOLIS, AND SIGFRED O. BYSTROM, OF ST. PAUL,
MINNESOTA

DESIGN FOR A RADIATOR CAP ORNAMENT

Application filed April 18, 1931. Serial No. 39,554. Term of patent 7 years.

To all whom it may concern:

Be it known that we, WILLIAM B. VANDEGRIFT and SIGFRED O. BYSTROM, a citizen of the United States and a subject of the King of Sweden, respectively, residing at Minneapolis, county of Hennepin, and State of Minnesota, and St. Paul, county of Ramsey, and State of Minnesota, respectively, have invented a new, original, and ornamental Design for Radiator Cap Ornaments, of which the following is a specification, reference be-

ing had to the accompanying drawings, forming a part thereof.

Figure 1 is a side elevation view of a radiator cap ornament showing my new design.

Figure 2 is a top plan view of the same.

We claim:

The ornamental design for a radiator cap ornament as shown.

WILLIAM B. VANDEGRIFT.
SIGFRED O. BYSTROM.
